UNITED STATES PATENT OFFICE.

GEORGE B. RAIT, OF MINNEAPOLIS, MINNESOTA, ASSIGNOR TO LOCOMOTIVE SUPER-HEATER COMPANY, OF NEW YORK, N. Y., A CORPORATION OF DELAWARE.

LOCOMOTIVE-SUPERHEATER.

1,147,815.

Specification of Letters Patent. Patented July 27, 1915.

Application filed April 7, 1913. Serial No. 759,315.

To all whom it may concern:

Be it known that I, GEORGE B. RAIT, a citizen of the United States, residing at Minneapolis, in the county of Hennepin and State of Minnesota, have invented certain new and useful Improvements in Locomotive-Superheaters; and I do hereby declare the following to be a full, clear, and exact description of the invention, such as will enable others skilled in the art to which it appertains to make and use the same.

My invention has for its object to provide an improved steam superheating device for use in connection with boilers of the locomotive type, and to such ends, generally stated, the invention consists of the novel devices and combinations of devices herein-after described and defined in the claims.

Particularly, this invention relates to that type of superheating apparatus wherein the superheating tubes are placed within large flues of the boiler in such manner that they are subjected to the heat from the products of combustion as they pass through the said flues. Hitherto, these superheating tubes have been extended on straight lines into the said large flues, from the front ends thereof, and then returned on straight lines to the front ends of the said flues. In the embodiment of my invention herein specifically shown and described I have made those portions of the superheating tubes which are within the flues, of spiral form, or in the form of coils. In superheating apparatus of this character, it is the common practice to extend the superheating tubes from a so-called saturated-steam header, into and then out of the flues, and from thence, to a so-called superheated-steam header.

The chief feature of this invention is directed to extremely simple and highly efficient means for accomplishing the connections between the superheating tubes and the said headers. Briefly stated, the chief novelty of this feature consists in providing the superheating tubes, at their ends, each with its own or individual coupling head. These so-called coupling heads are preferably in the form of sleeves having their axes at a right angle to the ends of the tubes to which they are applied, and the tubes are preferably welded thereto and arranged to receive from or deliver into said coupling heads, radially through one side thereof.

The coupling heads are adapted to be as-

sembled or massed together in axial alignment and in compact form, and to be secured to the respective headers by extremely simple and efficient means, hereinafter more fully described.

In the accompanying drawings which illustrate the invention, like characters indicate like parts throughout the several views.

Referring to the drawings, Figure 1 is a view partly in side elevation and partly in vertical section with some parts broken away, showing my improved superheater applied to a locomotive; Fig. 2 is a vertical section taken on the line $x^2 x^2$ on Fig. 6; Fig. 3 is a vertical section taken on the line $x^3 x^3$ on Fig. 6; Fig. 4 is a transverse vertical section taken approximately on the line $x^4 x^4$ on Fig. 1, some parts being broken away; Fig. 5 is an enlarged horizontal section taken on the line $x^5 x^5$ on Fig. 1, some parts being left in full; Fig. 6 is a view partly in plan and partly in horizontal section, and with some parts broken away, showing the two headers connected or designed as a single structure; Fig. 7 is a transverse section taken approximately on the line $x^7 x^7$ on Fig. 3, some parts being left in full; and Fig. 8 is a transverse section taken on the line $x^8 x^8$ on Fig. 5.

Of the parts of the locomotive boilers, the numeral 1 indicates the main shell, the numeral 2 the fire box, the numeral 3 the rear flue sheet, the numeral 4 the front flue sheet, the numeral 5 the smoke box, and the numeral 6 the smoke stack.

The numeral 7 indicates the dry pipe which extends from the front flue sheet 4 back to the steam dome, not shown.

The cylinder saddle 8 is a cast structure which, in its general features, is like the ordinary cylinder saddle, but differs therefrom in that it has upwardly extended-sleeve-like live steam passages 9 cast integral therewith. These steam passages 9 are curved at their lower portions but their upper end portions are straight and are true cylinders. These passages 9, as will of course be understood, lead to the steam chest.

Several of the horizontal upper rows of the flues, in the embodiment herein shown, are made of large diameter and are, of course, extended from the rear flue sheet 2 to the front flue sheet 4. As shown, there are four horizontal rows of these large flues

10. The small and lower flues are not shown, but would be of usual or any suitable arrangement. All of the flue tubes may be of the same diameter, however, within the spirit of the invention.

5 The so-called saturated steam header 11 is in the form of a hollow cast horizontally extended shell which has a receiving elbow 12 connected with a steam tight joint to the front flue sheet 4 and communicating directly with the front end of the dry pipe 7. The so-called superheated steam header 13 is a hollow cast structure very similar to the header 11, extends parallel therewith, and, 15 as shown, is integrally connected thereto by a multiplicity of connecting webs 14. The header 13 is provided with two coupling elbows 15 which are connected with steam tight joints to the upper ends of the steam delivery pipes 16. In accordance with one 20 of the above noted features of my invention, the lower ends of these steam delivery pipes 16 are connected to the upper ends of the steam passages 9 of the cylinder saddle by 25 telescopic sliding steam tight joints. These joints are advisably, and as shown, made by a plurality of packing rings 17 set into grooves in the enlarged cylindrical lower ends of the steam pipes 16 and telescoped 30 into the upper ends of the sleeve-like passages 9. These telescoped slip joints permit expansion and contraction of the pipes 16 and of other metallic parts, including the boiler shell, without offering any considerable 35 resistance to such movements, and without causing the said movements to strain or break any of the parts.

The superheating tubes 18 have one end connected to the header 11 and their other 40 ends connected to the header 13. This is accomplished in a novel manner, as already indicated. The header 11, for each vertical row of flues 10 is provided with a vertically extended cylindrical passage 19, the outer 45 end of which is threaded to receive a clamping plug 20, and the lower portion of which, for a considerable distance forward of the said plug, is formed with a slot 21 wide enough to receive the upper ends of the 50 superheated tubes 18. The sleeve-like coupling heads 22 which, as already stated, are welded or otherwise rigidly secured to the ends of the said tubes 18, are of such diameter that they are adapted to snugly fit 55 within the passage 19, and they are formed with beveled ends adapting them to be nested together with steam tight joints, and with steam tight joints with the plug 20 and with beveled seats 23 formed in the passages 60 19 (see particularly Fig. 2). In this way, when the plug 20 is tightened, the heads 22 will be securely locked to the header, causing 65 them to form a continuous steam tight conduit serving as part of or an extension of the coöperating passage 19. This construc-

tion also permits each tube unit to be applied or removed independently of any other, and also, adapt them to be assembled in any desired order or arrangement, except as controlled by the varying length, for different horizontal rows, of the upwardly bent unit ends. Also, one clamping device for each series of tube heads serves as efficient locking or clamping means.

The header 13 has steam passages 24 located adjacent to the steam passages 19 and corresponding thereto in number. These steam passages 24 have upturned rear ends, as best shown in Fig. 3, but their lower portions are truly cylindrical and are preferably parallel to the passages 19. The heads on the delivery ends of the flues 18 are like the heads 22 and are indicated by the character 22^a. The said passage 24 is provided with slots 21^a corresponding to the slots 21, 85 and the nesting heads 22^a are clamped together with steam tight joints by a plug 20^a, corresponding to the plug 20.

The intermediate portions of the superheating tubes 18 are bent to form spiral coils 18^a, that extend into the larger flues 10, through the front ends thereof and nearly to the rear ends thereof. These coils 18^a are double coils, and they may be made in different ways, integral or otherwise. As shown, however, they are made in two parts screwed together and with their inner rear ends connected by U-shaped couplings or return bends 25, which preferably have spacing lugs 26 that serve to hold the tubes 100 above the centers of the flues, as best shown in Fig. 8, so that the burning products of combustion find free passage at the bottoms of the said flues 10. This arrangement causes the products of combustion to pass between and around the turns of the coils, and thereby to maintain intimate contact with the said tubes throughout the passage thereof through the flues. Also, these coils tend to set up a whirling or spiral motion of the 105 products of combustion which retards their movement, and thereby obtains the maximum heating efficiency. Also, the coils very greatly increase the length of the tubes and correspondingly increase the heating surface 110 exposed to direct contact with the flames or products of combustion.

It is highly important to note that the double twist coils 18^a of the tubes of the superheater are at all points located above the lower internal surfaces of the flues, so that cinders will not be caused to lodge or accumulate within the flues. If the lower portions of the said coils were permitted to touch the bottoms of the internal surfaces of the flues, they would cause the cinders to stop and accumulate within the flues with obvious, very bad results.

I do not limit my invention, in its broader aspects, to the specific construction shown

and described herein as many details may be varied without departing from the spirit of the invention as defined by the claims. Thus while I have shown twisted super-
5 heater elements or tubes I may use the usual straight tubes and while I have shown a particular construction of nested tube head, other forms of heads may be employed without altering the character of the results
10 attained or detracting from the advantages obtained. My invention is, of course, quite independent of the particular type of headers used as well as of the general arrangement and location of said headers.

15 What I claim is:

1. A superheater comprising wet steam and superheated steam headers and superheating tubes connecting said headers, said headers having longitudinally slotted tubular passages opening thereinto, and the said tubes at their ends having sleeve-like heads nested together in axially alined rows within said tubular passages and clamped together therein with steam tight joints.

20 2. A superheater comprising wet steam and superheated steam headers, each having a plurality of slotted tubular passages opening thereinto, and superheating tubes connecting said headers and the said tubes, at 25 their ends, having sleeve-like heads axially nested together in rows within said tubular seats with the connected ends of said tubes passed through the slots thereof, and clamping plugs screwed into the ends of said tubular seats and holding the heads of the said tubes detachably but rigidly together with steam tight joints.

30 3. The combination with a boiler having flues, of a superheater comprising wet steam and superheated steam headers, each header having a plurality of slotted tubular passages opening thereinto, superheating tubes having coils extended into said flues and at 35 their ends having sleeve-like heads nested together in rows in said tubular passages, substantially as described.

40 4. The combination with a boiler having flues, of a superheater comprising wet steam and superheated steam headers, each header having a plurality of slotted tubular pas- 45

sages opening thereinto, superheating tubes having coils extended into said flues and at their ends having sleeve-like heads nested together in rows in said tubular passages, and threaded plugs in the ends of said tubular passages pressing the said sleeve-like heads together with steam tight joints, substantially as described.

55 5. In a flue tube boiler having a pair of headers and superheater tubes inserted in some of the flue tubes, individual sleeve like heads connecting said tube ends to the headers said heads being nested together.

60 6. In a flue tube boiler having a pair of headers and superheater tubes inserted in some of the flue tubes, individual sleeve like heads connecting said tube ends to the headers said heads being nested together in axially alined rows.

65 7. In a flue tube boiler having a pair of headers and superheater tubes inserted in some of the flue tubes, individual sleeve like heads detachably connecting said tube ends to the headers said heads being nested together.

70 75 8. In a flue tube boiler having a pair of headers and superheater tubes inserted in some of the flue tubes, individual sleeve like heads detachably connecting said tube ends to the heads said heads being nested together and to the headers.

80 90 9. In combination with a boiler having flues, a superheater comprising saturated and superheated steam headers connected respectively to steam supply and engine cylinders, superheater tubes in some of the flue tubes, and an individual head for each tube end said head having a passage the superheated ends and the saturated ends being independently grouped in rows with their heads nested together and with the passage in each head opening into its appropriate header.

95 In testimony whereof I affix my signature in presence of two witnesses.

GEORGE B. RAIT.
